D. Williams.

Tailors' Measure.

N^o

Patented

May 22. 1833

May 22, 1833

Daniel Williams of the City of New York
Seller's Patent May 22, 1833.

The Apparatus referred to in this Seller's Patent and making part of the
same containing a description in the words of the Said Daniel Williams
himself in the art of Tailoring.

To all whom these presents shall come: Be it known that Daniel
Williams of New York in the County of New York and State of New
York have invented a new and useful machine and improvement
in the art of Tailoring called the Mathematical Tailor's and that the
following is a full and exact description of the construction and opera-
tion of the Said Machine as invented by me.

1st A piece of Spring Steel or other metal about twenty one inches
long, more or less, and about an inch and a quarter wide and forming
a Strap. 2nd To each end of this Strap is attached a Spirit Level
placed in a small block of mahogany or other wood for the purpose of
adjusting the instrument whenever it is in use in a line exactly parallel
with the horizon. 3rd A thin or upright piece of metal attached to the
Strap near the right hand end and at right angles with its upper edge
to which is fastened a tape measure, not less than eighteen inches long.
4th The first described piece of metal or Strap is divided into inches and
half inches commencing at the upright stem and proceeding to the
left. 5th A piece of strap about seven inches long divided into half and
quarter inches with a band of the same metal attached to each ^{end} of it
and made to slide on the Steel Strap to the left hand end of which
is attached a tape measure, not less than ten inches long.

The following is the mode of using the machine. First place the
Strap close under the right arm with the upright stem close in front
of it taking great care that the coat or the vest may be not in doubt
under or in front of the arm so as to prevent the machine from going
close to the body. Second step the hand on the right hand side of
the Strap so that the thumb may form and bend and let the vest
or place the hand of his right hand on it to keep it on the right arm.

the body. Third. Place the right hand under the lower edge of the Steel and directly under the right arm with which the Steel is held upright by the arm, and it is not to be removed until the level is adjusted on the other end of the Steel and the four following measures are taken which are to be done with the left hand. 1st Slide the brap on the Strap to the left hand end of it. It shall touch the back seam of the coat on the costume and the number of inches it reaches on the Strap is to be entered in the measure book. This we shall call the cardinal measure.

2nd The tape measure on the front end of the Strap is to be passed up the shoulder to the prominent bone on the back part of the neck and then the number of inches in the measure book. This we shall call the neck measure. 3rd Pass now the tape measure over the shoulder about the sleeve head and down to the Strap at the same figure on the brap that was taken from the Strap, when the first or cardinal measure was taken or in other words the same as the figure on the Strap which the end of the brap still touches. This we shall call the shoulder measure.

4th The short tape measure attached to the brap is to be passed up the back seam to the bone before mentioned, at the back part of the neck.

(This we call the level measure. 5th Pass the measure just used across the breast to the front of the left arm. This we shall call the breast measure. Sixth. Take the level on the right hand end of the Steel in the right hand and hold it firmly against the breast of the costume with the bubble floating the upper edge of the Steel being close to the arm and the upright piece close to the front of it, as before; the measure fastened to the Steel. Now well now be taken, and passed up on a straight line with the edge of it holding it a little distance from the Steel.

Now the question is, where is the upper point of the front part of the coat in relation to this line carried up in front of the arm.

Is it in front of the line or back of it? Or will on a straight line with it, whichever it is must be taken, in your measure to judging of the quantity as near as possible of it be either in front or back of

the line. McMurphy
